PISTON EXPANDER

Wien C. Van Oort, Orange City, Iowa

Application December 31, 1934, Serial No. 759,845

3 Claims. (Cl. 309—12)

My invention relates to a device for expanding a piston of the usual type employed in reciprocating internal combustion engines.

An object of my invention is to provide a simple and convenient expanding arrangement which allows expansion of the piston to take up the contraction of the same due to friction.

A further object of my invention is to provide an expander which is light and which will not get out of order.

A further object of my invention is to provide an expander which will expand practically the entire length of the piston so that the seal between the piston and the cylinder wall will be efficiently maintained.

A further object of my invention is to provide an expander which is easy to install and which also provides means for retaining oil which otherwise would be thrown out of the piston sides.

A further object of my invention is to provide the above means in a structure of simplicity which can be manufactured at a very reasonable cost.

With these and other objects in view, my invention consists in the construction, arrangement and combination of the various parts of my device, whereby the objects contemplated are attained, as hereinafter more fully set forth, pointed out in my claims, and illustrated in the accompanying drawing, in which:

Figure 1 is a view of a piston including my expander taken from the bottom of the piston,

Figure 2 is a sectional view of Figure 1 taken along the lines 2—2 thereof,

Figure 3 is a principal view of the expander itself, and

Figure 4 is a sectional view of Figure 3 taken along the lines 4—4 thereof.

Many of the usual piston expanders now used utilize a structure which will only expand the skirt or the lower part of the piston.

One of the principal objects of my invention is to provide a structure which will efficiently expand the entire length of the piston.

I have used the character 10 to designate generally the piston of a combustion engine, which piston includes the small slot 11 which passes practically vertically up along the side thereof. This slot is made to allow for expansion through heat of the piston.

My device comprises the spring metal structure which is indicated generally by the character 12. This structure is made in one piece and includes the side walls 13 which terminate in the upwardly sloping flaps 14.

One end of the expander includes the arcuate portion 15 which is made in this shape to allow for contraction and expansion, and yet maintain the rigidity of the device.

The other end of the expander includes the end portion 16, bent approximately as shown, which is threaded at 17 to receive the bolt 18. The bolt 18 is received by the lock-nut 19.

The top of the device includes the upwardly projecting sides 20 (see Figures 2 and 4).

The side walls 13 include the circular openings 25, through which passes the usual piston pin 26. The opening 25 is made sufficiently larger than the size of the pin to allow for variation when the expander is used without interfering with the smooth operation of the pin.

It will be understood that the entire device can be made of one piece of spring material so that the same can be readily slipped into the piston as a complete unit.

In use the expander 12 is placed inside of the piston as shown in Figures 1 and 2 with the upper portion 20 resting against the rib 21 of the piston itself. This brings the extending ears 14 upwardly against the usual opening 22 (see Figure 2), which opening is present between the pin bearings and the sides of the piston. This provides a closure means which prevents oil from being thrown outwardly from the interior of the piston to the piston walls, thereby relieving the burden of the piston rings in sealing against too large a supply of oil being thrown up from the crank case of the engine.

After the device is placed in the piston as explained, it is expanded by means of the bolt 18 which is turned so that the end 23 thereof abuts against the inside of the piston wall, forcing the other end 15 against the other inner side. This operation expands the diameter of the piston by virtue of the usual slot 11 so that, when desired, expansion can be achieved, yet maintaining a perfect curvature of the piston.

As explained the portion 15 being arcuate absorbs any slight variations set up through expansion, and yet maintains the structure in its expanded condition.

It will be understood, of course, that after the device is placed inside of the piston that the pin and connecting rod are assembled as shown generally in the illustrations, and which allow the retention of the device so that the expander will be in place during the operation of the engine.

The lock-nut 19 is screwed on tightly against the threaded shoulder 24 to efficiently lock the bolt after the expansion operation is made.

It will now be seen that I have provided a piston expander which causes expansion of the piston along practically the entire length thereof.

It will be seen further that I have provided such 5 a device which is very light, thereby falling in line with general combustion practice, and it will be seen that I have provided means associated with the expander to prevent an excess of oil being thrown out through the piston walls, that I 10 have provided efficient means for absorbing heat expansion.

It will also be seen that I have provided all of the above mentioned means in a structure of great simplicity which can be manufactured at a 15 very reasonable cost.

I claim as my invention:

1. A piston expander comprising a shell adapted to be inserted inside a piston, said shell including an arcuate spring portion at one end 20 thereof for absorbing expansion and contraction when the spring portion is compressed against the inner wall of the piston, the other end of the shell including adjustable pressure means for

engaging the opposite inner wall of the piston.

2. A piston expander comprising a shell adapted to be inserted inside a piston, said shell including an arcuate spring portion at one end thereof for absorbing expansion and contraction 5 when the spring portion is compressed against the inner wall of the piston, the other end of the shell including adjustable pressure means for engaging the opposite inner wall of the piston, said pressure means including a bolt threadedly engaged with the said other end of the shell. 10

3. A piston expander comprising a shell adapted to be inserted inside a piston, said shell including an arcuate spring portion at one end thereof for absorbing expansion and contraction 15 when the spring portion is compressed against the inner wall of the piston, the other end of the shell including adjustable pressure means for engaging the opposite inner wall of the piston, said shell having integral baffle plates formed there- 20 with for covering exposed side openings in the piston.

WIEN C. VAN OORT.
